UNITED STATES PATENT OFFICE.

WILLIAM P. BOVARD, OF MANSFIELD, OHIO, ASSIGNOR TO THE OHIO BRASS COMPANY,
OF MANSFIELD, OHIO, A CORPORATION OF NEW JERSEY.

RAIL-BOND.

1,336,502.

Specification of Letters Patent. Patented Apr. 13, 1920.

Application filed November 2, 1917. Serial No. 199,958.

To all whom it may concern:

Be it known that I, WILLIAM P. BOVARD, a citizen of the United States, residing at Mansfield, in the county of Richland and State of Ohio, have invented certain new and useful Improvements in Rail-Bonds, of which the following is a specification.

This invention relates to electrical connectors and has particular reference to such classes known as rail bonds used for electrically connecting the adjacent ends of rails.

One object of my invention is to provide an improved device of this character which is simple and durable in construction, easily applied to the rails, effective in operation and which will give high electrical efficiency.

Another object of the invention is to produce a rail bond wherein provision is made whereby the body and terminal members can each be secured to the rails in various positions.

A further object of the invention is to produce a rail bond adapted to be welded to the surface of rails and having terminal members composed of metal having a higher melting point than the body member.

A still further object of the invention is to produce a rail bond having a terminal member composed of ferrous metal partially encircling the body member and adapted to be interlocked with the latter by compression of varying degrees of intensity.

To the attainment of these ends and the accomplishment of other new and useful objects, as will appear, the invention consists in the features of novelty in the construction combination and arrangement of the several parts hereinafter more fully described and claimed and shown in the accompanying drawings illustrating the embodiment of the invention, and in which:—

Figure 1 is a side elevational view of a rail joint showing the rails as electrically connected by a bond embodying the principles of my invention, the bond being shown in solid lines, in the position as usually applied to the rail in the type of joint illustrated, and in dotted lines in the position in which it may be applied to the rails in a different type of rail joint in which the constructional arrangement of the parts affecting the mechanical connection will not permit of the bond being applied in the former position.

Fig. 2 is a transverse sectional view of Fig. 1.

Fig. 3 is a side view of a bond embodying the principles of my invention.

Fig. 4 is a top view of the bond.

Fig. 5 is an end view of the bond.

Referring to the drawings in which similar reference characters indicate like parts in the different views (1—1) designate portions of two adjacent rails of an electric railway.

A bond consisting of a flexible body member 2, usually composed of a plurality of strands of copper, having securely attached to each end thereof a terminal member 3, composed preferably of ferrous metal having a higher melting point than the body, and embodying the principles of my invention is shown as electrically connecting the rails. The bond is secured to the rails by means of an attaching metal (4) which unites the terminal member (3) and the body member (2) to each other and to the rail by the application of heat.

The terminal member (3) is provided with a transverse slot or recess and partially encircles the body member (2), leaving a side surface (5), and the end surface (6), which projects a slight distance above the end surface of the terminal member exposed for receiving the attaching metal (4), and is secured to and interlocked with the body member (2), as clearly shown in Fig. 4.

For securing the bond to the rails in the position shown in solid lines, or the body portion thereof resting in a vertical plane, the attaching metal is welded to the end surface of the body member and in overlapping relation therewith.

When the bond is applied to the rails in the position as shown in dotted lines, or the body member thereof resting in a horizontal plane, the attaching metal is welded to the exposed side surface (5) of the body member and terminal member (3). It will be understood that my bond is equally adaptable to be applied to the ball of the rails in this position instead of to the base thereof as shown.

Attention is called to the fact that when the bond is applied to the rails in either position, the terminal member (3) and the body member (2) are each securely welded to the rail by means of the attaching metal (4), thus effecting a connection of high elec-

trical efficiency and of great mechanical strength.

The terminal member (3) is composed preferably of iron or steel and is first formed as shown in dotted lines Fig. 4, the sides or ends (7) extending in parallel relation to each other and forming a transverse recess or slot therebetween to snugly receive the end of the body member (2).

- 10 The body member (2) and terminal member (3) are assembled and the ends (7) of the terminal member (3) are then forced inward, toward each other in such manner as to securely lock the parts together by compressing the body member positioned within the transverse slot in a substantially wedge-shaped formation. The terminal member (3) is made of such size that the exposed faces thereof will present sufficient area for receiving the attaching metal as is necessary to give the strength required to secure the bond to the rail. The transverse slot or recess for receiving the body member is produced in any manner desired after 25 which it is further formed into the wedge-shaped formation to compress and lock the body member in place.

Having fully described my invention and illustrated the embodiment of the same, I do not wish to be limited to the details of the construction shown since these can be changed without departing from the spirit and scope of the invention.

I claim:

- 35 1. A rail bond comprising a flexible body

member, and a rigid terminal member, the terminal member having a transverse slot in one side face thereof to receive the body member and having the oppositely disposed sides of the terminal member inclined one 40 toward the other and engaging the body member which is interlocked therebetween.

2. A rail bond comprising a flexible body member, and a terminal member encircling three sides thereof, leaving one side and the 45 end surface of the body member exposed for receiving an attaching metal, the oppositely disposed sides of the terminal member being inclined, one toward the other, and engaging the body member which is interlocked there- 50 between and the remaining side of the terminal member.

3. A rail bond comprising a flexible body member and a rigid terminal member, the terminal member having a transverse slot in 55 one side thereof to receive the body member and having the oppositely disposed sides of the terminal member pressed into locking engagement with the body member.

4. A rail bond comprising a flexible body 60 and a terminal member composed of material having a higher melting point than the bond body; the terminal member encircling three sides of the body and having two sides thereof pressed into engagement 65 with the bond body in such a manner as to compress the latter therebetween into a substantially wedge-shape formation.

In testimony whereof I affix my signature,

WILLIAM P. BOVARD.
